(57) **CLAIM**

The ornamental design for a mounting and removing device for strap link as shown and described.

DESCRIPTION

FIG. 1 is a front, right and top perspective view of a mounting and removing device for strap link, showing my design.

FIG. 2 is another front, right and top perspective view of the mounting and removing device for strap link in FIG. 1.

FIG. 3 is a rear, left and bottom perspective view of the mounting and removing device for strap link in FIG. 1.

FIG. 4 is a front elevation view of the mounting and removing device for strap link in FIG. 1.

FIG. 5 is a rear elevation view of the mounting and removing device for strap link in FIG. 1.

FIG. 6 is a left side elevation view of the mounting and removing device for strap link in FIG. 1.

FIG. 7 is a right side elevation view of the mounting and removing device for strap link in FIG. 1.

FIG. 8 is a top plan view of the mounting and removing device for strap link in FIG. 1; and,

FIG. 9 is a bottom plan view of the mounting and removing device for strap link in FIG. 1.

The broken lines in the drawings depict portions of the mounting and removing device for strap link that form no part of the claimed design. The dash-dot-dash lines illustrate an unclaimed boundary of the claimed design.
